UNITED STATES PATENT OFFICE.

ALFRED H. DYSON, OF CHICAGO, ILLINOIS, ASSIGNOR TO MILO G. KELLOGG, OF CHICAGO, ILLINOIS.

TELEPHONE SYSTEM.

No. 899,787.

Specification of Letters Patent. Patented Sept. 29, 1908.

Application filed February 5, 1906. Serial No. 299,558.

To all whom it may concern:

Be it known that I, ALFRED H. DYSON, residing in the city of Chicago, county of Cook, and State of Illinois, have invented new and useful Improvements in Telephone Systems, of which the following is a specification.

My invention relates more particularly to multiple telephone-exchange switchboards. It has heretofore been the practice, in constructing switchboards of this character, to provide a line-signal for each subscriber's line and an answering spring-jack associated therewith, with operator's cord-connecting apparatus, whereby the operator connects 15 with a calling subscriber's line, learns the number of the called subscriber, and completes the connection by inserting a terminal of the cord-connecting apparatus in a multiple spring jack of the called line. In such 20 systems, multiple terminals of all subscribers' lines are placed within reach of each operator.

In the system herein shown, I retain the line-signal and answering-jack mentioned 25 above, but the multiple terminals of subscribers' lines are not placed within manual reach of the operator, but may be placed at any other convenient or desired point, the operator having control of electro-magnetically operated step-by-step switching mechanism, by means whereof she is enabled 30 to extend the line of the calling subscriber to multiple terminals of the called line, located at a distance from her position.

The object of my invention is to provide a 35 simple and efficient structure of the described character.

Among the advantages secured by my invention, may be mentioned the following: 40 Telephone exchange switchboards originally installed as non-multiple boards, and which it would be impossible to change over to a multiple system, should this become desirable, because there would not be space in the 45 switchboard cabinets for multiple spring jacks, may, by the employment of my invention, be readily converted into multiple boards, since, to change to a multiple system, as will be apparent from the description of 50 my invention, very little space in the switchboard is required.

Another advantage, which may be secured 55 by my invention, is found in its use when employed for trunking between distant exchanges. Hitherto, in manual exchange

practice, two operators have ordinarily been employed in such work, it being inexpedient from the viewpoint of cost and also switchboard space, to extend multiple circuits of lines terminating in one exchange to a distant exchange. By the employment of my invention, it is possible for an operator in one exchange to connect a calling subscriber's line with multiple terminals of subscribers located at a distant exchange without the intervention of a second operator, as will be more fully explained in the following description. It would, of course, not be practical to provide each subscriber's line, terminating in one exchange with multiple terminals at a distant exchange on account of the extreme expense that would be involved in so doing, consisting in providing an individual trunk circuit for each line extending from one exchange to the other. In the employment of my invention, a single trunk including three conductors extending from a spring jack at one exchange to the circuits of a connector switch at a second exchange provides facilities whereby an operator may connect a calling line at her own exchange with any one of a hundred subscribers' lines terminating at the distant exchange and having multiple terminals appearing in the banks of the said connector switch.

While I show and describe my invention in the form of a structure employing a single step-by-step switch only to complete a given connection which switch is, of course, a connector, it is not my intention to be limited to the employment of a single switch inasmuch as the employment of auxiliary switches of one or more classes in association with connectors, is well known in the art, having gone into extensive commercial use in the 90 United States. By the employment of auxiliary switches in association with connectors, it is, as is well-known, possible to select automatically any line desired out of a number as large as 10,000, or out of even a 100 greater number.

Referring to the drawings, Figure 1 illustrates a step-by-step switch, such as may be employed in connection with the circuits shown at E in Fig. 6, and H in Fig. 8; Fig. 2 illustrates a primary magnet of said switch and its associated parts. Fig. 3 illustrates a secondary magnet of said switch and its associated parts. Fig. 4 shows a sectional view of the switch-shaft together with the 110

primary magnet and its associated parts. Fig. 5 illustrates, in perspective side-switch arms and their associated contacts. Fig. 6 illustrates, diagrammatically, magneto telephone exchange circuits arranged in accordance with my invention. Fig. 7 illustrates a grounded magneto line circuit arranged in accordance with my invention. Fig. 8 illustrates a common-battery multiple switchboard telephone exchange system arranged in accordance with my invention. In Fig. 9 I show an arrangement whereby the spring jack terminal of the circuit H shown in Fig. 8 is provided with a busy test:

15 Referring to Fig. 1, the structure there shown is known in the art, and I do not claim it as my invention. A shaft 47^a is provided to which are rigidly attached wipers 32, 33 and 34. Associated with 20 wipers 32 and 33 is a bank of one hundred pairs of contacts arranged in vertical and horizontal rows of ten pairs each, the horizontal rows being curved so that the bank presents a concave surface. Associated 25 with wiper 34 is a bank of one hundred single contacts arranged in rows as described. All the contacts in the bank are insulated from each other and are multiple terminals of subscribers' lines. Shaft 47^a is journaled to the 30 frame of the banks and is capable of being raised upward with respect to the banks, by means of primary magnet 31, and of being rotated with respect thereto, by means of secondary magnet 40. By means of these 35 magnets, wipers 32 and 33 may be moved to engage any desired pair of contacts in their associated bank, the arrangement being such that wiper 34 at the same time will always engage a contact of its bank whose relative 40 location will correspond to that of the pair of contacts engaged. Each pair of contacts and its correspondingly located single contact form a set which constitutes the terminals of a single subscriber's line. Thus 45 the system is what may be called a three wire multiple switchboard. The cycle of operations for the switch shown in Fig. 1 is briefly, as follows:—Primary magnet 31 is operated to cause wipers 32, 33 and 34 to select 50 the desired levels of the contact banks. Private magnet 36 is then operated to throw side-switch arm 30 to engage its alternate contact 37. Secondary magnet 40 is thereupon operated to cause wipers 32, 33 and 34 55 to select the particular contacts desired from among those of the selected levels, such contacts forming the terminals of the particular line desired. Private magnet 36 is thereupon operated to throw side-switch arm 30 60 to engage the third contact 43. This completes the selection of the line. Release magnet 42 is provided for the purpose of restoring the switch at the end of conversation. It should be remarked at this time, that, 65 should the line whose terminals are selected,

as before described, be already in use, upon the second energization of private magnet 36, release magnet 42 is automatically operated to release the switch in order to prevent interference with an existing connection.

Assuming that it is desired to cause wipers 32 and 33 to engage the pair of contacts numbered 47 and 48 which would be terminals of line 89 of the one hundred lines terminating in the bank, eight impulses of current are caused to flow through primary magnet 31. The first of these, in attracting the magnet's armature, causes pawl 31^a, illustrated in Fig. 2, but which is concealed by its associated ratchet in Fig. 1, to engage the first tooth of the ratchet and lift the shaft a single step upward. The attraction of the magnet's armature also causes lug 31^b, attached thereto, to move arm 31^d to disengage double detent 31^c, which latter moves 70 toward the shaft, engaging with its upper portion a tooth of the vertical ratchet and holding the shaft in its raised position. The first movement of the shaft frees arm 30^b which, being pivoted as shown, is caused, by 75 its associated spring, to rotate about its pivot, releasing pawl 30^a preparatory to its movement as hereafter described. Successive impulses, caused to flow through magnet 31, lift, by means of pawl 31^a, the shaft 80 successive steps upward, detent 31^c engaging successive ratchet teeth after each thrust and maintaining the shaft raised. The teeth of the ratchet associated with pawl 31^a 85 are so spaced that each upward movement of the shaft brings the wipers to positions level with successive rows of horizontally disposed contacts. The next step in the operation of the switch is the energization and de-energization of private magnet 36. Said 90 magnet, in attracting its armature, causes a downward movement of ratchet 36^a attached to its armature, so that the lug 30^c upon side-switch pawl 30^a is brought to such position that it engages tooth *c'* of ratchet 36^a, the 95 said tooth being staggered with respect to tooth *c*. Upon the deenergization of magnet 36 and the retraction of its armature ratchet 36^a moves upward so that lug 30^c 100 slides down over tooth *c* and engages tooth 105 *b*. Pawl 30^a being pivoted as shown, and attached to arm 30, the latter is moved to disengage its normal contact and to engage 110 contact 37. Secondary magnet 40 is now 115 caused to be energized and deenergized nine 120 times. The shaft of the switch carrying wipers 32, 33 and 34, having been by the 125 eight impulses through primary magnet 31 raised to positions level with the horizontal rows of contacts including 47 48 and 49, the first impulse caused to flow through 40 by attracting its armature to which is attached pawl 40^a effects a thrust of the said pawl, which by engaging a tooth of its associated ratchet shown in Fig. 3, moves shaft 47^a in a 130

clock-wise rotary direction so as to bring wipers 32, 33 and 34 to engage the contacts at the extreme left of the selected rows. Each of the nine impulses mentioned effects a thrust of pawl 40^a, each thrust bringing the switch wipers into engagement with a successive pair of contacts and a single contact of the selected rows. The ninth and last impulse will, therefore, cause wipers 32, 33 and 34 to engage the contacts 47, 48 and 49 respectively, assumed to be terminals of the line desired which would, from the positions of the contacts in the banks be terminals of line 89 of the particular hundred lines having their terminals in the banks of the switch under description. Detent 31^c engages successive rotary ratchet teeth of the shaft holding it in each rotated position.

A second energization and deenergization of the side switch magnet 36 operating in a manner similar to that before described, brings the lug 30^c to engage tooth *a*, whereby side-switch arm 30 is moved to disengage contact 37 and to engage contact 43. When the release of the switch is desired, an impulse of current is caused to flow through release magnet 42, which by attracting its armature moves arm 42^a pivoted to the armature to the right, in such manner that the movement of its right extremity, which engages the pin shown upon the pawl 30^a, moves the pawl to such position, that lug 30^c is again brought into engagement with tooth *c*, rotating pawl 30^a and arm 30 to normal, the latter then engaging its normal contact. The described movement of arm 42^a to the right, by the engagement of the hook at its left extremity with the pin shown upon double detent 31^c moves the said detent away from the ratchets of the shaft and to such position that arm 31^d engages the upper pin upon detent 31^c, holding the detent in its retracted position. The disengagement of the shaft ratchets by detent 31^c leaves the shaft in a position to be freely rotated by spring 47^b, against the torsion of which the shaft was rotated in selecting terminals 47, 48 and 49. The shaft, therefore, rotates in a reverse clockwise direction until wipers 32, 33 and 34 reach a position beyond the contacts at the extreme left of the selected levels. When in this position, stationary detent 47^c, normally in such position as to be in the depression of the vertical ratchet shown in Fig. 2, but which with the first rotary movement of the shaft is always brought to engage a tooth of the vertical ratchet and so hold the shaft in its raised position while being rotated, is brought to a position where it again engages the said depression leaving the shaft free to descend to its normal position, which it does under the influence of gravity assisted by the tension of spring 47^b. As the shaft reaches its normal position it engages, with the lower edge of

the shaft ratchets, the left extremity of rocker arm 30^b which is thereby rotated about its pivot so that it assumes the position shown, in which its right extremity interlocks with pawl 30^a.

In Fig. 4 is shown a sectional view of the shaft disclosing fully the normal position of the stationary detent 47^c with respect to the vertical ratchet mounted upon shaft 47^a.

In Fig. 5 is illustrated the manner in which a plurality of circuit changing arms may be associated with pawl 30^a together with their appropriate sets of contacts, so that each movement of pawl 30^a may be employed to effect a plurality of simultaneous circuit changes. The customary off-normal switch including arm 29^a fastened to the upper portion of the shaft is provided, which, in this structure, is adapted with the first upward movement of the shaft to remove tension from the middle one of the three springs shown associated with it, whereby contact with the other upper spring is closed.

Referring to Fig. 6, I show at A, in diagrammatic form a local battery substation circuit including the usual hook-switch, generator, bell, transmitter, receiver and induction coil. 1 and 2 are the two limbs of the telephone line extending to the exchange, limb 1 being connected to spring 3 of the answering spring jack of the line, while 2 is connected to spring 10 of the spring jack. Normally in bridge of the two line limbs at the exchange is the winding of line drop 5, the circuit of which is arranged to be opened at a normally closed contact of switch spring 3 upon the insertion of a plug into the spring jack, and at a normally closed switching contact of cut-off relay 6 upon the energization of said relay. In multiple with switch spring 3 are switch contacts 47 and 47^a, while in multiple with switch spring 10 are contacts 48 and 48^a. The sleeve 9 of the spring jack is connected with the winding of cut-off relay 6 to the battery 11 and is multiplied to contacts 49 and 49^a. It will thus be seen that the subscriber's line is provided with the usual answering spring jack terminals and line drop and in addition is provided with terminal-contacts 47, 48 and 49 located in the contact banks of a connector such as that shown in Fig. 1, while contacts 47^a, 48^a and 49^a are located in the contact banks of a second such connector. Obviously the spring jack contacts of the line of A may be multiplied to as many connector contact banks as may be desirable for the operation of the exchange.

At D in Fig. 6 I show a cord circuit arrangement including the usual clearing out drop 50 shunted by a condenser, in order that its impedance may not affect the voice currents, the operator's talking set and listening-in key, together with a ringing generator 51 and the usual ringing key. In addition is

provided a calling device or dial 18 diagrammatically represented as a disk having upon its periphery ratchet teeth of insulating material, the disk being adapted for rotation in the direction indicated by the arrow, and being adapted upon its release after such rotation to return to normal in the opposite direction under the influence of the spring shown. This calling device is adapted when rotated and released to close contact between springs 21 and 22 a number of times dependent upon the extent of its rotation, and as it reaches normal to close contact a single time between springs 23 and 24. A stop is provided upon the device adapted, when the device is in other than its normal position to relieve tension from spring 20 whereby the said spring opens its normally closed contact with spring 19.

At 25 and 26, I have shown the levers of a key adapted when the said levers are thrown, to engage their alternate contacts to connect springs 21 and 24, associated with calling device 18, to contacts 14 and 16 of the calling plug of the cord circuit respectively.

At E, I have shown the circuits of a connector switch including primary magnet 31, secondary magnet 40, private magnet 36, release magnet 42, and a release relay 41 arranged to control the operation of 42. Side-switch arms 30, 35 and 35^a are provided with the usual normal, alternate and third contacts. Like parts appearing in Fig. 1 and at E in Fig. 6 have like reference characters. It is to be understood that the circuit at E is that employed for operating the switch structure shown in Fig. 1, the mechanical parts, other than the magnets of Fig. 1, being in general omitted in Fig. 6 for the sake of clearness in the circuit drawing. I have, however, shown the shaft and wipers 32, 33 and 34 associated with which wipers are contacts 47, 48 and 49, assumed to be located in a position corresponding to the location of 47, 48 and 49, shown in Fig. 1. To avoid confusion, the remaining contacts of the banks, wherein 47, 48 and 49 are included, are omitted in the circuit drawing. I have indicated at 47^a, 48^a and 49^a, multiple contacts of 47, 48 and 49, which are to be regarded as included in the banks of a connector switch, other than that shown at E, but having identical circuits and mechanism.

At B I have shown a second substation connected by its telephone line with its answering jack at the exchange, together with its associated line drop, and multiple connector switch contacts, the arrangement being in all respects the same as that shown in connection with substation A.

Assuming, for purposes of description, a magneto telephone exchange of 500 lines to be arranged in accordance with my invention and with circuits as shown in Fig. 6, the general arrangement of the switchboard would

be as follows:—The 500 lines would conveniently be divided into groups of 100 each, and a switchboard having five operators' positions would be provided, each operator having before her in the switchboard frame, line drops and answering jacks of the lines of one of these groups. The terminals at the exchange of each of the subscribers' lines of each group would be multiplied to a plurality of connector switches having circuits such as shown at E, appearing at said switches in the form of bank contacts. Each operator would be provided with a plurality of trunk jacks in addition to the before mentioned answering jacks, the said trunk jacks being terminals of connector switches. In an exchange of the size above specified, the provision at each operator's position of two trunk jacks, terminals of connector switches assigned for connection to each 100 line group (other than the group of the position), would under ordinary conditions of service give adequate facilities for the prompt completion of calls.

In completing connections between two subscribers both of whose lines have their line drops and answering jacks at her own position, the operator having tested the called line in the usual manner would complete the connection directly by the calling plug without the use of the selective switch. Thus, each of the 5 operators would have at her position 8 spring jack terminals of connector switches. Upon receiving a call from a subscriber of her own group, who desired to converse with a subscriber whose line is included in another group, the operator would insert the calling plug of the cord circuit D in a trunk jack of a connector assigned to the one hundred line group among which the line of the called subscriber is included, and would complete the connection by operating the calling device 18, which controls the connector switches. One calling device is provided for each operator's position, while a key is provided for each cord circuit enabling the operator to connect the calling device with any cord circuit desired, this being in a general way similar to the arrangement of the operator's talking set with respect to all of her cords. Obviously the connector switches may be placed at any convenient point in the same room with the switchboard sections, or in another room, or in a distant exchange, the only apparatus connected with them and required to be within reach of the operator being the spring jack terminals of the said connector switches.

The operation of the system is as follows:—Assuming that subscriber A desires to be connected with the line of subscriber B whose number is assumed to be 289; subscriber A operates the generator at the substation, current therefrom passing through the winding of drop 5 to attract its armature, releasing the drop shutter, which falls

and notifies the operator that her attention is desired. Subscriber A now removes his receiver, and hook lever moving upward thereupon connects the substation conversational circuit into operative relation with the line, at the same time, opening the signaling circuit. The operator, observing the signal, inserts the answering plug of cord circuit D into the spring jack of the 10 called line, tip 7 of the plug engaging contact 3 of the spring jack and simultaneously opening contact 3—4, cutting off the winding of drop 5 from limb 1 of the line. Upon the insertion of the plug, sleeve contact 8 15 connects with both of contacts 9 and 10. Current now flows from ground G^1 at the cord circuit, through contact 8—9, winding of cut-off relay 6 to the active side of battery 11, energizing the cut-off relay which at 20 attracts its armature. It will be seen that ground G^1 is at this time connected to private contacts 49, 49^a, etc., connector terminals of the calling line, the said line being thereby rendered busy with respect to connector switches having access to it, in the 25 well known manner. The operator now throws over levers 12—13 of her listening key and learns from the calling subscriber the number of the line wanted. Assuming 30 the line wanted, No. 289, to be included in a group other than that whose lines have their spring jacks in front of the operator, she raises the calling plug of the cord circuit used in answering and inserts it into the 35 spring jack of a trunk circuit connected to a connector switch, assigned to lines Nos. 200 to 299 inclusive. On the insertion of the plug, auxiliary spring 15^a is caused to disengage contact 29. The connector selected 40 is assumed to be that whose circuit is shown at E. The operator restores her listening key, and throws over levers 25 and 26 of her calling key, thus placing calling device 18 in operative relation with the connector switch. 45 The operator now rotates dial 18 until eight teeth have passed to the right of spring 21. Released, the dial returns in the opposite direction closing and breaking contact eight times between springs 22 and 21. With 50 each closure of contact between said springs, an impulse of current flows from ground G^2 through contact 22—21, through lever 27 of the ringing key, lever 25 of the calling key, plug and jack contact 14—15, side 55 switch arm 30, primary magnet 31 to the active side of battery 11. The primary magnet is thereby energized and deenergized eight times and lifts the shaft of the connector eight steps upward, bringing 60 wipers 32—33, and 34 level with the eighth rows of horizontal contacts of their associated banks, counting from below. The ninth contacts counting from the left of 65 these rows will be the terminals of line 89 of the particular group or of line 289.

With the return of the dial 18 to normal, contact is closed and broken between springs 24 and 23 a single time at a period subsequent to the last closure between springs 22 and 21. An impulse of current is thereby 70 caused to flow from ground G^2 through springs 23—24, lever 28, lever 26, plug and jack contact 16—17, side switch arm 35, private magnet 36 to the active side of battery 11. 36 is thereby energized and deenergized, whereby arms 30, 35 and 35^a disengage their normal contacts and engage contact points 37, 38 and 39 respectively, as will be understood from the preceding description of Fig. 1. The operator now causes nine 80 impulses of current, by the operation of dial 18, to be transmitted from ground G^2 through contact 22, 21, lever 27, lever 25, plug and jack contact 14—15, contact 30—37, through the winding of secondary magnet 40 to battery 11. The resulting energizations and deenergizations of secondary magnet 40 cause nine rotary step-by-step movements of the switch shaft bringing wipers 32, 33 and 34 into engagement with contacts 47, 48 and 49, 90 forming multiple terminals of the desired line. With the return of dial 18 to normal a single impulse of current flows from ground G^2 over the before traced path to side switch arm 35, through contact 38 and the winding 95 of private magnet 36 to battery 11, causing a second energization and deenergization of 36, which causes arms 30, 35 and 35^a to engage contacts 43, 44 and 45 respectively. Arms 30 and 35, in leaving their alternate contacts 100 37 and 38 to engage contacts 43 and 44, cut off secondary magnet 40 and private magnet 36 from the talking strands of circuit E, indicated by the heavy lines. By engaging contacts 43 and 44 they complete the talking circuit of E through to wipers 32 and 33 and to the limbs of the called-for line. Arm 35^a by engaging contact 45 connects ground G^5 to private wiper 34 and private contact 49 and its multiples of the called-for line, rendering 110 the line "busy" with respect to other connector switches having access to it. Sleeve contact 9 of the spring jack of the called line is also connected to ground G^5 , thereby providing a busy test for the called line, inasmuch as the tip contacts of the calling plugs of all operators' positions are connected to battery when the listening key is depressed, so that the operator having charge of the line at B, will, under these conditions receive a 115 "click" in her telephone upon touching the tip 14 of the plug to sleeve contact 9 of the spring jack of the line of subscriber B. The closing of 35^a—45 also effects the energization of cut-off relay 6 of the called line which 120 attracts its armature to open the circuit of drop 5. The operator connecting the lines of subscribers A and B now throws her levers 27 and 28 of her ringing key, connecting generator 51 in circuit with the line of sub- 125 130

scriber B, and causing his bell to ring. She thereupon restores levers 27-28 and also levers 25-26 of the calling key, thereby completing connection between the two subscribers' lines and conversation proceeds upon the response of the called subscriber, the talking circuit being traced from substation A, over the heavily marked line conductors, through cord circuit D, over the heavily marked conductors at connector circuit E, and over the heavily marked line conductors of the line of subscriber B.

When the subscribers have finished their conversation, they replace their receivers and operate the substation generators. When either one does so, current from his generator flows through the winding of clearing out drop 50 at cord circuit D. The armature of said drop is attracted and the drop shutter falls, thus notifying the operator that conversation is finished. She thereupon withdraws the answering plug from the calling subscriber's line, restoring the line circuit to normal. She also withdraws the calling plug from the trunk jack. Jack spring 15 thereupon resumes its normal position, and auxiliary contact 15^a again engages contact 29. With the first upward movement of the connector shaft when initially operated, off-normal switch 29^a engaged its front contact. Hence, at the closing of contact 15^a-29, current will flow from ground G³ through said contact, through switch arm 29^a, and winding of release relay 41 to the battery 11. Contact is, by the resulting energization of 41, closed from ground G⁴ through the winding of release magnet 42 to battery 11 and the release magnet attracts its armature restoring the switch to normal, as described in connection with Fig. 1. The line of subscriber B is thereby placed in its normal position, and the busy test potential is removed from sleeve contact 9 of its spring jack.

45 I will now describe the means whereby, should the line of the called subscriber be already in use, when the wipers of a connector switch are brought to rest in engagement with contact-terminals of said line, the connector will automatically be released and returned to normal. It will be noted that if a subscriber's line is a busy line, due to a connection having been made by a plug of a cord circuit such as D to its spring jack, sleeve contact 9 of the line jack and its multiple contacts 49-49^a will be connected to ground G¹ at the cord circuit; on the other hand, if the line is busy, due to connection having been made therewith by a connector, its sleeve contact 9 and its multiple contacts 49-49^a will be grounded at ground G⁵ of the connector. Assuming that the line of subscriber B is busy, and contact 49 therefore grounded, at the time wipers 32, 33 and 34 of switch E engage terminals 47, 48 and 49 re-

spectively, it will be observed that when the impulse of current flowing from ground G², with the return of calling device 18 to normal, through contact 23-24, levers 28 and 26, contacts 16-17, 35-38, through private magnet 36, causes the energization of the said private magnet, there will, upon the engagement of armature of 36 with its associated front contact, be established a path for the flow of current as follows: from grounded contact-terminal 49 of the called line, through wiper 34, and contact 35^a-39 (the switch arms being moved only upon the de-energization of the private magnet) through armature of private magnet 36, its front contact, winding of release relay 41 to battery 11. The energization of 41 closes circuit through release magnet 42 and the connector switch returns to normal. This is the means above referred to, whereby a connector will be automatically released when its wipers are caused to engage terminals of a busy line, the result being that an existing conversation cannot be interfered with. Upon the release of the switch, occurring at this time, the operator receives a busy signal from the interrupter 46 as soon as side switch arm 30, with the release, is brought to engage its normal contact. The path for the interrupted flow of current notifying the operator that the called line is busy when the connector is released, may be traced from interrupter 46, by induction through condenser 46^a, through its normal contact to side switch arm 30, contact 15-14 through lever 25 (at this time depressed) through lever 27, through contact 19-20 (dial 18 being at this time in its normal position) through the operator's receiver and to battery 11. It will be noted that this path is independent of the position of levers 12 and 13 of the listening key. The operator, upon hearing the signal at this time, withdraws the plugs, after advising the calling subscriber that the line wanted is busy. It will be noted that the operator immediately on inserting the calling plug into the spring jack of a connector and depressing the levers 25 and 26 of the calling key, will receive the busy signal until such a time as side switch arm 30 is moved, under the influence of 36, to disengage its normal contact and to engage its alternate contact 37. The operator however, pays no heed to the signal at this time, under instructions to this effect.

110 In Fig. 7, I show the arrangement of a substation C, the line circuit at the exchange employing a single line conductor 1, the other conductor 2 shown in Fig. 6 being dispensed with, ground indicated at 2^a, 2^b and 2^c being employed in its place. This arrangement is adapted for use in connection with the cord circuit shown at D and the connector shown at E of Fig. 6.

115 120 125 130 In Fig. 8, I show the application of the

broad features of my invention to a multiple telephone exchange system of a well known character. The substations F and G are illustrated, extending by their line limbs 1 and 2 to the exchange, and there provided with answering and multiple spring jacks, one only of the latter being shown. Said lines, in addition to the spring jacks, are provided with multiple terminals forming bank contacts of connector switches. The general arrangement of the bank contacts may be such as that described in connection with Fig. 6, as may be the division of the lines into groups, one group being assigned 15 to each of a plurality of operators. The provision for each operator of two or more trunk spring jacks connected to connector switches assigned to individual groups of one hundred subscribers' lines would be retained. The substation at F is arranged for common battery talking, and comprises the usual hook-switch normally maintaining the condenser and call-bell in bridge of the two line limbs, the said switch being adapted 20 upon removal of the receiver to place the bell in open circuit and connect the transmitter into circuit with the metallic circuit of the line. The signaling circuit for the line at the exchange is of well known character, 25 comprising the line relay 50 controlling by its armature the local circuit of the line lamp 51. Forming a part of the line circuit is also the cut-off relay 53 connected to the sleeve contacts of the spring jacks and adapted 30 upon the insertion of a plug into the spring jack to open the circuit of the line relay and connect the two line limbs to the multiple connection terminals of the line. The cord circuit shown at Fig. 8 is also of well known 35 character, including an answering plug comprising contacts 55 and 59, associated with which are the supervisory relays 56 and 58, under whose joint control is the answering supervisory lamp 57. The cord circuit includes also the calling plug comprising contacts 63 and 65, associated with which are the supervisory relays 70 and 72, controlling 40 jointly the calling supervisory signal lamp 71. A test relay 75 is provided, normally in 45 circuit with the tip contact of the calling plug in the usual manner. An operator's talking circuit is also provided and a listening key comprising levers 61 and 62 individual to the cord circuit for connecting the 50 talking set with a subscriber's line. The arrangement of generator 51 and its associated ringing key is also well known in the art. For each operator's position is provided a dial or calling device 18, similar to that already 55 described in connection with Fig. 6, and for each cord circuit is provided a calling key, comprising levers 25 and 26 adapted for placing the dial 18 into operative relation with the calling plug.

At H in Fig. 8, I have shown a connector

circuit differing from that shown at E principally in respect to the arrangement for releasing the switch as will be more particularly pointed out hereafter. The mechanical features of the switch operated by means of 70 circuit H may be substantially the same as those disclosed in Fig. 1 with the following exceptions. First, that wiper 34 is omitted together with its associated contact bank, two wipers 32 and 33 only being required in 75 connection with the circuit arrangement of H; secondly, the off-normal switch shown at 80 is arranged, with the first upward movement of the switch shaft, to disengage its associated contact instead of engaging it, as 80 off-normal switch 29^a shown at E in Fig. 6 is arranged to do. The substation shown at G is provided with a circuit similar to that of the substation at F and its line circuit at the exchange is similar to the line circuit 85 connected with substation F.

Assuming, that the subscriber F desires to be connected with the subscriber G, whose number is 289, subscriber F, by removing his receiver, closes circuit through line relay 90 50, which by attracting its armature effects the illumination of line lamp 51. The operator observing the signal inserts the answering plug into the answering jack, closing contacts 59—60 and 55—54. Current flows 95 from ground G^a through cut-off relay 53, through contact 54—55, supervisory relay 56 to the active side of battery 52. This causes the energization of cut-off relay 53, which by attracting its armature connects 100 the limbs of the line to contacts 54 and 60 of the spring jacks. Relay 56 is energized also, and by the attraction of its armature would cause the display of supervisory lamp 57, were it not for the fact that relay 58, is, upon 105 the energization of cut-off relay 53, energized by a flow of current from ground G^a through 58 over the line of F returning through contacts 54—55 and the winding of 56 to battery. The operator throwing over 110 levers 61 and 62 of the listening key learns the number of the desired subscriber, 289. Were this subscriber provided with a line jack within reach of the operator, she would 115 test the said jack by touching tip 63 of the calling plug to its sleeve contact, receiving, in case the line is busy, the usual "click" in her head telephone from the resulting actuation of the test relay 75, in which case she would advise the calling subscriber that the 120 line is busy. Did she hear no "click," she would complete the call in the usual manner. Assuming, however, that the called line is not provided with a spring jack within reach of the operator, she inserts the calling plug 125 of the cord circuit into the spring jack terminal of connector H, among the bank contacts of which the line of subscriber G, numbered 289, is assumed to have multiple terminals. The operator, throwing over levers 130

25 and 26 of her calling key, first operates the dial 18 to send eight impulses of current from ground G^2 through contact 22—21, levers 26 and 28, contact 65—66, arm 30, primary 5 magnet 31 to battery. Magnet 31 is thereby caused to effect upward movements of the shaft of the connector to bring wipers 32 and 33 level with rows of contacts including terminals of Nos. 281 to 289 inclusive followed 10 by 280. A single impulse of current now flows from ground G^2 through contact 23—24, levers 25 and 27, contact 63—64, private magnet 36 to battery lead 52^a. Private magnet 36 by its energization and deenergization moves side switch arms 30, 35 and 35^a to engage contacts 37, 38 and 39 respectively.

The operator now actuates dial 18 to send nine impulses of current from ground G^2 over 20 the previously traced path to side switch arm 30, through contact 37, secondary magnet 40 to battery lead 52^a. The resulting energizations of magnet 40 bring wipers 32 and 33 to engage multiple contact terminals of the desired line. With the return of dial 18 to normal, a single impulse of current again flows from ground G^2 through the private magnet 36 to battery; the said magnet, by its resulting energization and deenergization, moves 25 side switch arms 30, 35 and 35^a to engage their respective third contacts 43, 44 and 45, assuming the called line to be idle. The closing of contacts 30—43 and 35—44 connects the talking conductors of H, indicated by 30 heavy lines, through to wipers 32 and 33 and to contacts 47 and 48 now engaged by said wipers. The called line being assumed idle, the operator receives no busy signal, and restores levers 25 and 26 of her calling key, 35 whereupon current flows from ground G^2 at the line circuit of subscriber G through cut-off relay 53, contacts 47—32, 43—30, 66—65, through levers 28 and 26, the winding of supervisory relay 70 to battery 52. Cut-off 40 relay 53 is now energized and attracts its armatures to open the circuit of the line relay 50 and to connect limbs 1 and 2 of the line of subscriber G to contacts 48 and 47 respectively and to the other multiple terminals of 45 the line. The before described flow of current also effects the energization of relay 70 which attracts its armature to engage the associated front contact, thereby closing circuit from ground G^2 through calling supervisory 50 signal lamp 71 to battery 52, effecting the display of the said signal. The energization of 55 relay 70 also attracted its right hand armature to open the circuit of test relay 75 and complete the conversational circuit of the tip strand of the cord circuit in the well known manner.

The operator now depresses levers 27—28 60 of her ringing key, connecting generator 51 in circuit with the called line, current from said generator passing through the call bell 65 at the substation and causing the bell to ring,

thus notifying the subscriber that his attention is desired. While the bell of subscriber G is being rung, cut-off relay 53 is continued energized by a flow of current from ground G^2 , passing through ringing key lever 28 and its alternate contact to battery lead 52^a. The operator restores levers 27 and 28 and when the called subscriber G responds, by removing his receiver, a path for the flow of current is established from ground G^2 through tip supervisory relay 72, the right hand armature of relay 70, through levers 25 and 27, contacts 63—64, 35—44, 33—48, its alternate contact and armature 53^a over limb 1, through the transmitter and hook lever at the substation, returning over limb 2 through armature 53^b and its alternate contact, through contacts 47—32, 43—30, 66—65, levers 28 and 26 and the winding of relay 70 to battery 52. This flow causes the energization of relay 72 which, by attracting its armature opens the circuit through lamp 71, which is thereby put out, thus notifying the operator that the called subscriber has responded. The above traced flow of current energizes the transmitter of subscriber G and conversation now proceeds over a path traced from substation F throughout the exchange by the heavily marked conductors to substation G, condensers 73 and 74 being included in the two strands of the talking circuit at the exchange in the well known manner.

When at the end of conversation the subscriber at F replaces his receiver, he opens 100 the path for the flow of current through relay 58 before traced, which relay is deenergized, and as a result its armature engages its back contact to complete a path for current to cause the display of supervisory signal 57. 105 When the subscriber at G replaces his receiver, he opens the before traced path for the flow of current through relay 72, which is deenergized, its armature retracted, and a path for current closed through supervisory lamp 71, which is thereupon displayed. Both lamps being thus lighted the operator 110 knows that conversation is finished. She thereupon withdraws the answering plug from the spring jack of the line of the subscriber F and the calling plug from the spring jack of circuit H. The first withdrawal opens the circuit through relays 56 and 53, whose armatures resume their normal positions, whereby lamp 57 is extinguished and 115 line relay 50 placed in circuit with the calling line.

It will be observed that mechanically connected to the tip contact 64 of the spring jack of circuit H is an auxiliary contact 67 adapted, when tip 63 of the calling plug engages spring 64, to close contact 67—67^a, whereby circuit is completed from ground G^2 through said contact and through the 120 windings of relays 69 and 68 in series to bat- 125 130

tery lead 52^a. Thus, when a plug is first inserted into the spring jack of H, relays 68 and 69 are immediately energized and remain so during the subsequent switching operations and during conversation. Of these two relays 5 68 is constructed in such manner as to be relatively sluggish in the release of its armature as compared with relay 69, the arrangement of the two being such that when they 10 are simultaneously deenergized upon the withdrawal of the plug from the spring jack of H and the resulting opening of contact 67—67^a, the armature of 69 will be retracted to close its normal contact before the armature of 68 disengages its associated front contact. 15 To render 68 relatively sluggish as to the release of its armature, a copper shell may be placed about its core or it may be rendered sluggish in any other known or approved manner. Thus, when the operator removes the calling plug from the jack of circuit H, contact 67—67^a is opened and circuit through 68 and 69 is opened. The quickly acting armature of 69 closes circuit 20 25 from ground G¹³ through release relay 41, the armature of 69, the armature of 68 to battery lead 52^a. 41 attracts its armature to energize release magnet 42 and the connector is released and returns to normal. When the 30 35 sluggishly acting armature 68 disengages its front contact, circuit will be broken through 41 and, upon the retraction of the armature of 41, release magnet 42 is deenergized and the connector switch is in its normal condition.

It will be observed that when a plug is inserted into the spring jack of any line, a connection exists to the sleeve of the spring jack from the active side of battery 52, and contact 47 in the connector banks being in multiple with the sleeve of the line jacks, said battery connection extends to said contact 47 and its multiples. Similarly, when wiper 32 is brought to rest in engagement with a contact 47 of an idle called line, a battery connection 40 45 to the contact 47 and its multiples, and to the sleeve contacts of the multiple spring jack of the line, is completed from the active side of battery 52. In either of these cases, the potential of the spring jack sleeves is 50 raised so that an operator, testing a spring jack with the calling plug, will always receive a "click" in her receiver.

The battery connection above mentioned to contacts 47 of busy lines is employed 55 in securing the automatic release of connectors whose wipers 32 are brought to rest in engagement with contacts 47 of busy lines in the following manner. Assuming the line of G to be busy when 32 engages 47, the energization of relay 36 occurring with the return 60 of dial 18 to normal, as before described, attracts the armature of 36 to engage its associated front contact. At this time, 35^a will be in engagement with 39, it being remembered 65 that the side-switch arms are ac-

tuated only upon the deenergization of 36. Current thus flows from ground G¹³ through release relay 41, through armature of 36 to its front contact, through contact 35^a—39, wiper 32 to bank contact 47 and to battery 70 through a multiple of the said bank contact. This flow energizes the release relay 41, which, in turn, energizes release magnet 42, upon whose energization the connector is released and returns to normal. With the return thereof, contact 80—81, which was opened with the first upward step of the shaft, is again closed and the operator receives a busy signal from busy machine 46, through contact 80—81, the normal contact 80 of side-switch arm 30, plug and jack contact 66—65, lever 28, lever 26, its alternate contact, through contact between springs 19 and 20 (dial 18 being at this time at normal) and through the tertiary winding of the operator's induction coil to battery. The operator, being thus notified that the line wanted is busy, withdraws the calling plug from the jack of the connector used, and, advising the subscriber of the circumstances, withdraws 90 the answering plug from the spring jack of the line.

While in the foregoing I have described each operator as being provided with jack terminals of connector switches individual to her position, I contemplate, in the employment of my invention, a structure wherein the spring jack terminals of connector switches may be multiplied before two or more operators, each of whom would be thus enabled to use them in completing a desired connection. In doing this, it is preferable to provide a busy test for the spring jack terminals of the connectors, and in Fig. 9 I have indicated one way in which the test means 100 105 may be provided for spring jacks of connectors such as that shown at H in Fig. 8.

The additional means provided in Fig. 9 consist merely in the provision of a second sleeve contact 66^a for each multiple terminal of a connector switch, the said additional sleeve contacts being connected together. In employing this multiple arrangement the circuit connections of the connector will be identical with those shown at H and the 110 115 same cord circuit as that shown in Fig. 8 will be employed.

Assuming that the operator desires to test, by means of the cord circuit shown at Fig. 8, one of the multiple jacks shown at Fig. 9, she 120 touches the tip 63 of the calling plug to sleeve 66^a of the jack to be tested. If the jack tested is idle, 66^a will be in open circuit, and no energization of the test relay 75 in the cord circuit will result and the operator will receive no click in her telephone. She will thereupon insert the plug into the spring jack, tip 63 of the plug engaging contact 64 of the jack and sleeve 65 of the plug crossing contacts 66 and 66^a of the spring jack. It 125 130

will be seen from an inspection of Fig. 8 that sleeve 65 is at all times connected to the active side of battery 52 with the exception of the time when calling device 18 is being operated. Sleeve contacts 66^a of the multiple connector spring jacks, will, when the calling plug of a cord circuit is inserted in one of them, be connected to the active side of 52. A second operator touching the sleeve contact 66^a of a multiple jack in which a plug is inserted will cause a flow of current from ground G⁹, through test relay 75 to tip 63 of the plug with which she is making a test, thence to contact 66^a of the plug tested and through a multiple thereof to the active side of battery 52. Test relay 75 will therefore be actuated and attracting its armature will close circuit through the tertiary winding of the operator's induction coil, notifying her that the connector in circuit with the multiple jack tested is already employed by an operator at another position.

I do not limit myself to the specific arrangement of apparatus and circuits shown herein or to the employments specifically mentioned of my invention, as the principle is applicable broadly in the art, and I shall so claim it.

I claim:

30 1. A telephone system comprising subscribers' telephone lines extending from substations to an exchange, signals for said lines controlled from the substations, operators' answering means adapted for connection with said lines, other telephone lines, multiple terminals for said other lines, selective switches adapted to be employed for making connection therewith, operators' switching means to enable the operators to transmit 40 directive currents to said selective switches to cause them to connect said answering means with terminals of particular ones of said other telephone lines whereby connections between subscribers are completed, and 45 a central source of current and branches to supply current therefrom for conversation.

2. A telephone exchange system including telephone lines having answering terminals at the exchange, signals at the exchange adapted to be controlled by currents over said lines, operators' connective means adapted to be connected with said answering terminals, multiple terminals of said lines at the exchange, selective switches adapted for operation to complete connections from said answering terminals to said multiple terminals, operators' switching means for controlling the operation of said switches to select terminals of particular lines, means for changing the electrical character of its terminals to render them busy when connection is made with a line; automatic test means for said switches sensitive to the electrical character of said terminals to render connections ineffective 65 when said terminals are busy, a central

source of current and branches to energize subscribers' transmitters therefrom for conversation, and means for releasing said selective switches when disconnection is required.

3. A multiple switchboard telephone exchange system including telephone lines, signals for said lines at the exchange, answering jacks for said lines, operators' cord circuits provided with plugs for connecting with said spring jacks, multiple calling terminals of said lines divided into groups, a plurality of connector switches adapted to make connections with the lines of each of said groups, means controlled by the operators for completing connections from said cord circuits to said connector switches, calling devices controlled by the operators for transmitting directive switching currents to said switches to cause them to select particular called lines of their groups, means for changing the electrical character of its terminals to render them busy when connection is made with a line, test means for said switches whereby a connection made with a busy line is ineffective, and a central source of current and apparatus for supplying current therefrom to subscribers' lines for conversation.

4. A multiple switchboard telephone exchange system including telephone lines, signals for said lines at the exchange, answering spring jacks for said lines, operators' cord circuits provided with plugs for connecting with said spring jacks, multiple calling terminals of said lines divided into groups, a plurality of connector switches adapted to make connections with the lines of each of said groups, manually manipulated operators' switches for connecting said cord circuits with said switches, calling devices controlled by the operators for transmitting directive switching currents to said switches to cause them to select particular called lines of their groups, means for changing the electrical character of its terminals to render them busy when connection is made with a line, test means for said switches whereby a connection made with a busy line is ineffective, and a central source of current and apparatus for supplying current therefrom to subscribers' lines for conversation.

5. A multiple switchboard telephone exchange system including subscribers' lines, signals for said lines adapted for operation from the substations, answering spring jacks for said lines, multiple calling terminals of said lines divided into groups, a plurality of connector switches adapted to make connection with the lines of each of said groups, link-circuits extending to said switches for controlling their operation, spring jack terminals of said circuits, operators' cord circuits having answering plugs for connecting with said answering spring jacks and calling plugs for connecting with said spring jack terminals, calling devices controlled by the

operators for transmitting directive switching currents to said switches to cause them to select particular lines of their groups, automatic test means for said connector switches to cause them to avoid busy lines, and a central source of current and branches therefrom to supply current for conversation.

6. A multiple switchboard telephone exchange system including subscribers' lines, 10 signals for said lines adapted for operation from the substations, answering spring jacks for said lines, multiple calling terminals of said lines divided into groups, a plurality of connector switches adapted to make connection with the lines of each of said groups, link-circuits extending to said switches multiple spring jack terminals of said circuits, means enabling the operators to determine the idle or busy condition of said spring jack 15 terminals, operators' cord circuits having answering plugs for connecting with said answering spring jacks and calling plugs for connecting with said spring jack terminals, calling devices controlled by the operators for transmitting directive switching currents to said switches to cause them to select particular lines of their groups, automatic test means for said connector switches to cause them to avoid busy lines, and a central 20 source of current and branches therefrom to supply current for conversation.

7. A multiple switchboard telephone exchange system including telephone lines, signals for said lines at the exchange, answering spring jacks for said lines, operators' cord circuits provided with plugs for connecting with said spring jacks, other telephone lines, multiple terminals of said other lines divided into groups, a plurality of connector switches adapted to make connections with the lines of each of said groups, manually manipulated operators' switches for connecting said cord circuits with said connector switches, calling devices controlled by the 40 operators for transmitting directive switching currents to said switches to cause them to select particular lines of their groups, and a central source of current and apparatus for supplying current therefrom to subscribers' 45 lines for conversation.

8. A multiple switchboard telephone exchange system including telephone lines, signals for said lines at the exchange, answering spring jacks for said lines, operators' cord circuits provided with plugs for connecting with said spring jacks, other telephone lines, multiple terminals of said other lines divided into groups, a plurality of connector switches adapted to make connections with 50 the lines of each of said groups, manually manipulated operators' switches for connecting said cord circuits with said connector switches, calling devices controlled by the operators for transmitting directive switching currents to said switches to cause them

to select particular lines of their groups, means for changing the electrical character of its terminals to render them busy when connection is made with a line, test means for said switches whereby a connection made with a busy line is ineffective, and a central source of current and apparatus for supplying current therefrom to subscribers' lines for conversation.

9. In a telephone system, a plurality of 75 trunk jacks, a trunk line connected thereto, an automatic switch connected to said trunk line, waiting contacts in said automatic switch, contact wipers in said switch adapted to engage said waiting contacts, and means 80 adapted to release and restore to normal position the contact wipers upon the withdrawal of a plug from one of said jacks.

10. A telephone exchange system including subscribers' lines, answering terminals 85 and signals for said lines at the exchange, calling terminals for said lines, operators' connecting means comprising manually movable terminals for connecting with said answering terminals, electromagnetically movable terminals for connecting with said calling terminals, and a slow acting release relay and a quick acting release relay associated with said electromagnetically movable terminals adapted at the will of the operator to co-operatively cause the restoration 90 of said terminals.

11. A telephone system comprising subscribers' telephone lines extending from substations to an exchange, signals for said lines 100 controlled from the substations, operators' answering means adapted for connection with said lines, other telephone lines, multiple terminals for said other lines, selective switches adapted to be employed for making connection therewith, operators' switching means to enable the operators to transmit directive currents to said selective switches to cause them to connect said answering means with terminals of particular ones of 105 said other telephone lines whereby connections between subscribers are completed, a spring jack switch and a plug therefor adapted to connect said switching means with a selective switch, and apparatus operable, when said plug is removed from said spring jack switch, to cause the restoration 110 of an operated selective switch.

12. A telephone system comprising subscribers' telephone lines extending from substations to an exchange, signals for said lines controlled from the substations, operators' answering means adapted for connection with said lines, other telephone lines, multiple terminals for said other lines, selective 120 switches adapted to be employed for making connection therewith, operators' switching means to enable the operators to transmit directive currents to said selective switches to cause them to connect said an- 125

swering means with terminals of particular ones of said other telephone lines whereby connections between subscribers are completed, automatic test means for said switches adapted to automatically cause their disconnection from busy lines when brought to engage terminals thereof, a spring jack switch and a plug therefor adapted to connect said switching means with a selective switch, and apparatus operable, when said plug is removed from said spring jack switch, to cause the restoration of an operated selective switch.

13. A multiple switchboard telephone exchange system including telephone lines, signals for said lines at the exchange, answering terminals for said lines, operators' link-circuits for connecting with said answering terminals, other telephone lines, multiple calling terminals for said lines, selective switches for connecting with said last mentioned terminals, link-circuits connected with said selective switches, manually operated terminals for said link-circuits adapted for connection with said operators' link-circuits, and apparatus operated on disconnection of said operators' link-circuits from said manually operated terminals for restoring said selective switches.

14. A multiple switchboard telephone exchange system including telephone lines, signals for said lines at the exchange, answering terminals for said lines, operators' link-circuits for connecting with said answering terminals, other telephone lines, multiple calling terminals for said lines, selective switches for connecting with said last mentioned terminals, link-circuits connected with said selective switches, manually operated terminals for said link-circuits adapted for connection with said operators' link-circuits, means for causing the operation of said selective switches to connect with said other telephone lines, apparatus for changing the electrical character of said multiple terminals to render them busy when said switches are connected with said other lines, test means for said selective switches whereby they automatically disengage said multiple terminals when busy, and apparatus operated on disconnection of said operators' link-circuits from said manually operated terminals for restoring said selective switches.

15. A telephone exchange system including telephone lines having answering terminals at the exchange, signals at the exchange adapted to be controlled by currents over said lines, operators' connective means adapted to be connected with said answering terminals, multiple terminals of said lines at the exchange, selective switches adapted for operation to complete connections from said answering terminals to said multiple terminals, operators' switching means for controlling the operation of said switches to select

terminals of particular lines, and plug and jack connections included in said operator's switching means adapted, when a plug is removed from a jack, to cause the restoration of a connected selective switch.

16. A telephone system including a calling line, an operator's link-circuit connected therewith, other telephone lines, multiple terminals for said other lines, selective switches adapted to be employed for making connection therewith, operators' switching means to enable the operators to transmit directive currents to said selective switches to cause them to connect said answering means with terminals of particular ones of said other telephone lines whereby connections between subscribers are completed, and a central source of current and branches to supply current therefrom for conversation.

17. A telephone exchange including a substation, a telephone line connecting said station with the exchange, signals at the exchange, a hook-switch at the substation adapted, on removal of the receiver, to cause the display of a signal, operators' means for answering the call, other telephone lines, multiple terminals for said other lines, selective switches adapted to be employed for making connection therewith, and operators' switching means to enable the operators to transmit directive currents to said selective switches to cause them to connect said answering means with terminals of particular ones of said other telephone lines whereby connections between subscribers are completed.

18. A telephone exchange including a substation, a telephone line connecting said station with the exchange, signals at the exchange, a hook-switch at the substation adapted, on removal of the receiver, to cause the display of a signal, operators' means for answering the call, other telephone lines, multiple terminals for said other lines, selective switches adapted to be employed for making connection therewith, operators' switching means to enable the operators to transmit directive currents to said selective switches to cause them to connect said answering means with terminals of particular ones of said other telephone lines whereby connections between subscribers are completed, a central source of current and branches to supply current therefrom for conversation.

19. A telephone exchange including a substation, a telephone line connecting said station with the exchange, signals at the exchange, a hook-switch at the substation adapted, on removal of the receiver, to cause the display of a signal, operators' means for answering the call, other telephone lines, calling terminals for said other telephone lines and operators' connecting means including electromagnetically movable termi-

nals for completing connections through to said other telephone lines.

20. A telephone exchange including a substation, a telephone line connecting said station with the exchange, signals at the exchange, a hook-switch at the substation adapted, on removal of the receiver, to cause the display of a signal, operators' means for answering the call, other telephone lines, 10 calling terminals for said other telephone lines and operators' connecting means in-

cluding electromagnetically movable terminals for completing connections through to said other telephone lines, and test means for said calling terminals to render connections ineffective when said lines are busy. 15

In witness whereof, I hereunto subscribe my name this 30th day of January, 1906.

ALFRED H. DYSON.
